UNITED STATES PATENT OFFICE.

ARCHIBALD W. DINGMAN, OF TORONTO, ONTARIO, CANADA, AND HENRY H. ARGUE, OF DERRICK CITY, ASSIGNEES OF ONE-THIRD OF THEIR RIGHT TO JOHN J. CARTER, OF TITUSVILLE, PENNSYLVANIA.

ELECTRIC HEATER FOR OIL-WELLS.

SPECIFICATION forming part of Letters Patent No. 231,287, dated August 17, 1880.

Application filed May 3, 1880. (No model.)

To all whom it may concern:

Be it known that we, ARCHIBALD W. DINGMAN, a citizen of the Dominion of Canada, and HENRY H. ARGUE, a citizen of the United States, residing, respectively, in the city of Toronto, county of York, Province of Ontario, and Derrick City, county of McKean, State of Pennsylvania, have invented a new and useful Improvement in Electrical Apparatus, of which the following is a description.

The object of our invention is to heat and liquefy the paraffine in the tubing and in the rock of oil-wells, to start the flow of gas and oil, thereby increasing the production, and to heat the oil in oil-tanks, for the purpose of freeing it from the ice-water and other foreign substances, which retard the ready flow of oil from the tanks through pipe-lines; and to that end our invention consists in an apparatus through which a current of electricity is passed, whereby sufficient heat is evolved in the machine to melt the paraffine in the tubing and rock of oil-wells and heat the oil in oil-tanks when brought into contact with the paraffine and the oil. We attain these objects by the mechanism illustrated in the accompanying drawings, in which—

Figure 1 is a vertical section through the entire apparatus or machine, and Figs. 2 and 3 vertical sections of parts thereof.

Similar letters refer to the same parts in the different figures.

In the drawings, *a* represents a carbon rod surrounded by a layer of mineral asbestos, *b*, and inclosed in a brass tube, *c*. At opposite ends of the brass tube *c* are brass screw-caps *d* and *e*, with circular openings *f* and *g* in their centers. The carbon rod *a* is suspended in the brass tube *c* by means of brass head-pieces *h* and *h'*, fitting exactly the ends of the carbon rod *a*. The opposite ends of these head-pieces *h* and *h'*, reduced in circumference from a shoulder and threaded, pass through the openings *f* and *g* in the brass screw-caps *d* and *e* and are adjusted by the brass nut *i* and the brass screw-cap *j*. On the screw-caps *d* and *e* are lugs *k* and *l*, through which passes the copper rod *m*, the opposite ends of which are threaded. Through the screw-cap *j* passes a brass pin, *n*,

adjusted by a brass nut, *o*, and terminating at 50 the opposite end in a threaded socket, *p*, into which the one end of the copper rod *m* screws. The screw-cap *e* is extended in the form of or has attached thereto a hollow cone, *q*, which terminates in a point, *x*. An extension of one 55 side of the cone *q* forms a recess, in which the connection of the copper rod *m* with the screw-cap *j* is made by means of the brass pin *n*. The copper rod *m* is insulated with asbestos and wound with fine brass wire, to protect 60 it from possible abrasion. The connections through the openings are protected by the brass caps *t* and *u*, vertical sections of which are given in Figs. 2 and 3.

The brass head-pieces *f* and *g*, brass nut *i*, 65 and screw-cap *j* are insulated with asbestos from contact with the brass screw-caps *d* and *e* and brass tube *c*, and the covers or caps *t* and *u* are also insulated by asbestos from contact with the connection at *o* and *p*. 70

To carry our invention into effect we connect the machine with the positive and negative conducting-wires of an electrical generator by means of flexible insulated copper cables at *w* and *y*. A current of electricity passes into 75 the machine at *w*, through the screw-head *f*, into the carbon rod *a*, from the carbon rod *a* into the screw-head *h'*, through the screw-cap *j*, into the pin *n*, to the copper rod *m*, back to the negative conducting-cable at *y*. 80

The resistance which the electric current meets with in its passage through the semi-conducting carbon rod *a* evolves in the carbon a volume of heat. This is transmitted to the non-combustible asbestos packing *b b*, which 85 conducts it to the surrounding brass tube *c*. The asbestos *b b*, while being non-combustible, readily conducts the heat generated in the carbon *a*, and at the same time, being a non-conductor of electricity, insulates the carbon 90 rod against possible contact with the brass tube *c*.

By running this machine or apparatus down into an oil-well we bring it into contact with the paraffine, which soon heats and melts, allowing the gas confined below it to ascend and causing the oil to flow. 95

By placing the apparatus in the oil in tanks

sufficient heat is evolved to free the oil from foreign substances, thereby allowing it to flow readily from the tanks into the pipe-lines.

As the paraffine becomes hardened at different depths in different wells, by having our electrical heater arranged to evolve the required heat within itself without the aid of any exterior apparatus, we are enabled to raise and lower the machine at will by means of the flexible conducting-cables *w* and *y*, thereby bringing it in contact with the paraffine in the well at whatever depth it may have become hardened in the tubing without in any way breaking the circuit of the electrical current.

The conical lower portion of the machine, composed of the hollow cone *q* and the covers *t u*, serves to puncture any thick accumulation of paraffine contained in the well, and, in connection with the tube *c*, protects the carbon rod or circuit-interrupter and its connections from any possible short-circuiting against the tubing of the well.

Having fully described our invention, what we claim, and desire to secure by Letters Patent, is—

1. The combination, in an electrical machine or apparatus, of the carbon rod *a*, the asbestos packing *b b*, and the brass tube *c*, for the purpose of evolving heat by electricity, substantially as specified.

2. In an electrical machine or apparatus for liquefying oil in wells and tanks, the combina-

tion, with a tube, *c*, of the screw-caps *d e*, having circular openings *f g*, and the adjustable head-pieces *h h'*, for the purpose of suspending the carbon rod *a*, substantially as shown and described.

3. The combination, in an electrical heater, of the copper rod *m* and the screw-caps *d e*, having lugs or bearings *k l*, with the pin *n*, screw-cap *j*, head-pieces *h h'*, and carbon rod *a*, all arranged substantially as and for the purpose set forth.

4. In an electric heater, the combination, with a metallic tube, *c*, of the screw-cap *e*, hollow cone *q*, and covers or caps *t u*, all constructed and arranged substantially as and for the purposes described.

5. The electrical machine or heater herein described, consisting, essentially, of a metallic tube containing a carbon rod, connected by suitable devices with a copper rod on the exterior, the various parts being provided with a non-combustible insulating material, and the whole suspended by means of flexible conducting-cables arranged in such a manner that the machine may be raised and lowered at will within the tubing of oil-wells, so as to come in direct contact with and liquefy the paraffine and oil at any depth, substantially as specified.

ARCHIBALD W. DINGMAN.
HENRY H. ARGUE.
